[57] CLAIM

The ornamental design for a therapeutic heat transfer wrap, as shown and described.

DESCRIPTION

FIG. 1 is a perspective view of a therapeutic heat transfer wrap showing my new design in use;

FIG. 2 is a front elevational view of the wrap in nonuse position;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line showing of a limb in FIG. 1 is for illustrative purposes only and forms no part of the claimed design.
